Louis Gioggia INVENTOR
BY
Kiddle and Marston ATTORNEYS.

UNITED STATES PATENT OFFICE.

LOUIS GIOGGIA, OF WEST NEW YORK, NEW JERSEY, ASSIGNOR TO ST. MUNGO MANUFACTURING COMPANY OF AMERICA, OF NEWARK, NEW JERSEY, A CORPORATION OF NEW JERSEY.

DESIGN FOR A GOLF BALL.

Application filed September 10, 1927. Serial No. 23,355. Term of patent 14 years.

To all whom it may concern:

Be it known that I, LOUIS GIOGGIA, a citizen of the United States, residing at West New York, county of Hudson, and State of New Jersey, have invented a new, original, and ornamental Design for Golf Balls, of which the following is a specification, reference being had to the accompanying drawing, forming part thereof.

Fig. 1 is an elevational view of a golf ball showing my new design; and

Fig. 2 is a diagrammatic plan view thereof.

I claim:

The ornamental design for a golf ball as shown.

Dated, New York, N. Y., September 9, 1927.

LOUIS GIOGGIA.
